Primary Examiner—Cathy Anne MacCormac**[57] CLAIM**

The ornamental design for an ink tank for printer, as shown and described.

DESCRIPTION

FIG. 1 is a front view of a ink tank for printer showing my new design thereof;

FIG. 2 is a rear view thereof;

FIG. 3 is a top plan view thereof;

FIG. 4 is a bottom plan view thereof;

FIG. 5 is a left side view thereof;

FIG. 6 is a right view thereof; and,

FIG. 7 is a perspective view thereof.

1 Claim, 1 Drawing Sheet*FIG. 1*

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 387,086

DATED : December 2, 1997

INVENTOR(S) : TOSHIAKI SASAKI

It is certified that error appears in the above-identified patent and that said Letters Patent is hereby corrected as shown below:
